DESIGN FOR A GUARD FOR HIGHWAY MARKINGS

Harvey F. Elliott, Cleveland, Ohio, assignor to Louis S. Wertz, Inc., Cleveland, Ohio, a corporation of Ohio

Application March 22, 1940, Serial No. 91,154

Term of patent 7 years

To all whom it may concern:

Be it known that I, Harvey F. Elliott, a citizen of the United States, residing at Cleveland, in the county of Cuyahoga and State of Ohio, have invented a new, original, and ornamental Design for a Guard for Highway Markings, of which the following is a specification, reference being had to the accompanying drawing, forming a part thereof.

In the drawing the figure is a perspective view of a design for a guard for highway markings,
showing my new design.

I claim:

The ornamental design for a guard for highway markings, substantially as shown.

HARVEY F. ELLIOTT.
